UNITED STATES PATENT OFFICE

123,220

DESIGN FOR A RESTAURANT BUILDING OR SIMILAR ARTICLE

John F. Dobben, Merrimac, Mass., assignor to J. B. Judkins Company, Merrimac, Mass., a corporation of Massachusetts

Application April 24, 1940, Serial No. 91,919

Term of patent 3½ years

To all whom it may concern:

Be it known that I, John F. Dobben, a citizen of the United States, residing at Merrimac, in the county of Essex and State of Massachusetts, have invented a new, original, and ornamental Design for Restaurant Building or Similar Article, of which the following is a specification, reference being had to the accompanying drawing, forming part thereof, in which

Fig. 1 is a front perspective view of a restaurant building showing my new design;

Fig. 2 is a top plan view thereof; and
Fig. 3 is an end elevational view.

The rear wall is plain except for necessary doors and windows.

I claim:

The ornamental design for a restaurant building or similar article, as shown and described.

JOHN F. DOBBEN,
